[57] CLAIM

The ornamental design for a cap, as shown and described.

DESCRIPTION

FIG. 1 is a front elevational view of a cap showing our new design;

FIG. 2 is a side elevational view thereof, the opposite side is a mirror image;

FIG. 3 is a top plan view thereof;

FIG. 4 is a rear elevational view thereof; and,

FIG. 5 is a front perspective view thereof.

The broken line showing of the face shown on the cap is for illustrative purposes only and forms no part of the claimed design.
